UNITED STATES PATENT OFFICE.

WORTHY C. BUCKNAM, OF JERSEY CITY, NEW JERSEY, ASSIGNOR TO DAVIS-BOURNONVILLE COMPANY, OF NEW YORK, N. Y., A CORPORATION OF NEW YORK.

BLOWPIPE APPARATUS.

1,096,095.

Specification of Letters Patent.

Patented May 12, 1914.

Application filed September 5, 1913. Serial No. 788,222.

To all whom it may concern:

Be it known that I, WORTHY C. BUCKNAM, a citizen of the United States, and a resident of Marion, Jersey City, in the 5 county of Hudson and State of New Jersey, have invented certain new and useful Improvements in Blowpipe Apparatus, of which the following is a specification.

This invention relates to metal-cutting apparatus of the kind wherein the cutting, so-called, is effected by a jet or jets of oxygen acting in conjunction with a heating jet or jets. The apparatus is more particularly one for mechanically propelling the jets so 10 as to follow the contour of an object to be severed, for example a rail, the invention having for its object to provide an efficient and comparatively simple apparatus whereby cuts of this character can be made 15 accurately and very expeditiously.

The invention is herein disclosed in its preferred embodiment, but the principles of construction and mode of operation may be embodied in numerous specifically different devices.

In the accompanying drawings illustrating the said preferred form of the invention: Figure 1 shows the device in front elevation applied to a rail which has been 20 partially cut, through the operation of one part of the apparatus. The torch is shown mounted in the left-hand part of the apparatus, two other positions at this side being indicated by dotted lines and corresponding 25 positions being indicated by dotted lines at the right-hand side of the apparatus. Fig. 2 is a similar view of the apparatus without the torch and with the movable parts shown in different positions from Fig. 40 1. Fig. 3 is a side elevation, the supporting frame and the primary operating shaft being sectioned for clearness of illustration and the rail being indicated by dotted lines. The torch-holder is shown mounted in one 45 of the sockets therefor, but for simplicity of illustration the torch is omitted. Fig. 4 is a fragmentary sectional plan view illustrating part of the gearing and the hinged joint between the frame parts.

50 The jet-delivering means or cutting device proper may be of any suitable construction. It will be apparent that it could be a built-in part of the apparatus, but pref-

erably it is attachable and detachable, and, as hereinafter described, interchangeable between the two parts of the apparatus, so that one cutting device serves for both sides of the rail.

The construction illustrated is designed to accommodate a standard form of cutting torch, designated 10 in Fig. 1. The construction and operation of such torches are well known in the art, and therefore do not call for detailed explanation. For a better understanding of the construction of the general kind of torch illustrated, reference may be had to my prior Patent No. 1,044,741, dated November 19, 1912, for cutting torch. The combustible gas, as acetylene, is supplied through the flexible tube 11, and the oxygen, both for cutting and heating, through the flexible connection 12. In some torches the supplies of oxygen for cutting and heating are led through separate flexible tubes. In the type of torch illustrated, the oxygen stream is divided by branched passages within the torch, the flow of heating oxygen being accurately regulated by a needle valve 13 and the cutting oxygen being adapted to be turned on and off by a valve 14, while a common valve 15 may be used to turn the oxygen and acetylene for all the jets on and off simultaneously. The gases proceed through the torch; the oxygen and acetylene for the heating jet or jets are mixed by suitable provisions; and the cutting oxygen is delivered from an orifice 16, while the heating jets formed of the combustible mixture emerge from the orifices 17. There may be one or more of the heating jets; and, while the heating and cutting jets are shown as discharged from a single nozzle or tip 18, it will be understood that they could be discharged from separate nozzles with the same effect.

95 The apparatus comprises two parts, adapted to be positioned at opposite sides of a rail or the like. The particular apparatus illustrated is designed for severing rails of the form represented at 19. Naturally, the form and construction are susceptible of variation, according to the character of the object to be cut.

The apparatus includes a suitable support, the preferred embodiment of which 105 consists of two frame parts 20 and 21,

at its lower end meshing with another bevel gear 48 on the same shaft with a pinion 49, the latter meshing with a gear 50 on the shaft 32 of the rotary member 30. Through 5 these instrumentalities, turning of the handle 51 causes the rotary member to turn in a substantially regular manner irrespective of the depressions and elevations in the cam.

The left-hand part of the apparatus is 10 a substantial duplicate of the right-hand part, though the shape of the cam is naturally different because of the difference in the two sides of the rail. Furthermore, since as indicated in Fig. 1 the depth of 15 the right-hand cut renders it unnecessary for the nozzle of the torch to follow closely into the corners of the left-hand side of the rail, the low parts of the cam 31^a, corresponding to these internal corners, may be 20 made as shallow as may be desired. The rotary member 30^a mounted on its shaft 32^a, the slide 34^a, the traveler 36^a, the spring 53^a, the shaft 46^a and the gearing 45^a, 47^a, 48^a, 49^a 25 and 50^a may be all substantially like the similar parts at the right-hand side of the apparatus.

A desirable feature of the invention resides in the construction whereby a single torch may be used in either part of the apparatus and quickly transferred from one to 30 the other. For this purpose the slides or torch-bearing members 34, 34^a are provided with tubular projecting sockets 55, 55^a for the reception of a stem 56 projecting at 35 right-angles from a torch-holder 57. The latter is in the nature of a split collar, within which the cylindrical body of the torch 10 may be clamped, and may be provided with a stem 56 at each side. The stem is 40 adapted to be held frictionally in the socket 55 and to be readily inserted and removed therefrom; and an important detail is the provision of means for locating the torch-holder in proper angular relation with reference 45 to the driving and guiding mechanism. This is accomplished in a simple manner by providing the stem of the torch-holder with a key or keys 58, which engage in key-ways 59, 59^a cut in the interior of the 50 sockets 55, 55^a. The torch can thus be positioned in proper angular relation at once, and no time is lost in transferring the torch from one side of the apparatus to the other.

To cut a rail, the apparatus is clamped 55 thereon as shown in the views. The right-hand side is preferably cut first, and while the cut may progress either up or down, the torch in its starting position is preferably directed downward, so as to deliver its jets 60 against the outer edge of the basal flange. The jets having been established, the handle 51 is rotated, so as to cause the jets to progress inward across the flange, thence upward along the web, and finally outward beneath 65 the tread, the guiding means con-

trolling the path of the jets throughout the operation in the manner already described. This produces a cut substantially as shown in Fig. 1, that is to say, the web, the tread and the right-hand basal flange of the rail are entirely cut through, and the cut also extends a certain distance into the left-hand flanges. The driving mechanisms at the two sides of the apparatus are geared together and driven by the common primary shaft 37; and the arrangement is preferably such that when the right-hand cut has been completed the left-hand mechanism is ready to receive the torch in the position shown in full lines in Fig. 1. The torch is quickly transferred from the right-hand part of the apparatus to the left-hand part, and the operator then turns the other handle 52, so as to cause the jets to travel downward at the left-hand side of the rail. The upper flange is thus cut through, and when the upper end of the first cut is reached the jets may be turned off, to be re-established again when the nozzle is opposite the basal flange. The whole operation can be performed in an exceedingly short space of time, and produces a clean and satisfactory cut. The provision of the two handles 51, 52 is desirable, because it enables the operator to turn both in the same direction.

Both the cams 31, 31^a and the shoes 23, 24 are detachable, as shown, so that by substituting different sets of cams and shoes the apparatus may be adapted to cut rails or objects of different contours.

While the apparatus illustrated has been described in detail for clearness of understanding, it will be understood that the invention is not limited to details, nor is it limited to the application described. For example, similar principles of construction and operation would serve for welding, by the substitution of a welding torch for a cutting torch.

In certain of its aspects the present invention resembles that disclosed in my prior application Serial No. 743,768, filed January 23, 1913, and comes within the scope of the generic claims contained therein.

What I claim as new is:

1. A device adapted to be affixed to a rail or the like for expeditiously severing the same by means of gases, comprising means of attachment to a rail or the like, a cutting torch movably supported by said attaching means, and mechanism distinct from the work for propelling and guiding said torch so as to cause its jets to travel across the inner surfaces of the rail or the like and to turn the internal corners between the web and lateral projections thereof.

2. Apparatus of the character described, comprising jet-delivering means, means for movably supporting the same in operative relation to the side of a rail or the like,

the slide at the opposite side of said axis from the delivery end of said jet-delivering means, and a cam track disposed for co-operation with said traveler to confine said delivery end to a predetermined path.

15. An apparatus of the character described, comprising a rotary member, means whereby heating and cutting jets can be delivered in a plane intersecting the axis 10 of rotation of said member, said means being connected with said member so as to be angularly propelled thereby and being capable of movement relatively to said axis, and a guide controlling said movement, in 15 combination with mechanical means for driving said rotary member in a substantially uniform manner.

16. In an apparatus of the general character described, the combination of a suitable support, a rotary member, a slide engaging said rotary member, cam means controlling the movement of said slide relative to said rotary member, jet-delivering means attachable to said slide in position to operate in a plane transverse to the axis of rotation of said rotary member, and means for locating said jet-delivering means angularly in proper relation to said cam means.

17. In an apparatus of the general character described, the combination of a suitable support, a rotary member, an element adapted to be angularly driven by said rotary member and also capable of movement relatively thereto, cam means for controlling the latter movement, detachable jet-delivering means carried by said element and directed in a plane transverse to the axis of rotation of said rotary member, and means for locating said jet-delivering means angularly in proper relation to said cam means.

18. Apparatus for rail-cutting and the like, comprising two parts adapted to be disposed at opposite sides of a rail or the like, each part comprising rotary driving mechanism, guiding means, and jet-delivering means adapted to be propelled by said driving mechanism and confined by said guiding means to a path substantially conforming to the contour of the work.

19. Apparatus for rail-cutting and the like, comprising two parts adapted to be disposed at opposite sides of a rail or the like, each part comprising rotary driving mechanism, and guiding means, in combination 55 with common means for driving the driving mechanisms of both parts of the apparatus.

20. Apparatus for rail-cutting and the like, comprising two parts adapted to be disposed at opposite sides of a rail or the like, each part comprising rotary driving mechanism, guiding means, and an element turned by said driving mechanism and also moved in an eccentric manner under the influence of said guiding means, in combination 65 with a cutting torch and means for ap-

plying the same to either of said elements to operate in a plane transverse to the work.

21. Apparatus for rail-cutting and the like, comprising two parts adapted to be disposed at opposite sides of a rail or the like, each part comprising rotary driving mechanism, guiding means, and an element turned by said driving mechanism and also moved in an eccentric manner under the influence of said guiding means, in combination 70 with a torch holder, and means for quickly socketing the same to either of said elements.

22. Apparatus for rail-cutting and the like, comprising two parts adapted to be disposed at opposite sides of a rail or the like, each part comprising rotary driving mechanism, guiding means, and an element turned by said driving mechanism and also moved in an eccentric manner under the influence of said guiding means, in combination 75 with a torch, means for quickly socketing the same to either of said elements, and means for locating the torch in proper angular relation to the guiding means of each 80 part of the apparatus.

23. Apparatus for rail-cutting or the like, comprising a frame having two relatively movable parts adapted to be disposed at opposite sides of a rail or the like, a rotary member mounted on each frame part, mechanism for driving said rotary members, a cam track on each frame part, and a torch-supporting element turned by said rotary member and guided by said cam track so 90 that the jets substantially follow the contour of the work.

24. Apparatus for rail-cutting or the like, comprising a frame having two relatively movable parts adapted to be disposed at opposite sides of a rail or the like, a rotary member mounted on each frame part, gearing carried by each frame part for driving the corresponding rotary member, common means for operating said gearings, a 95 cam track on each frame part, and a torch-supporting element turned by said rotary member and guided by said cam track so that the jets substantially follow the contour of the work.

25. Apparatus for rail-cutting or the like, comprising two hinged frame parts adapted to receive a rail or the like between them, a rotary member mounted on each frame part, mechanism for driving said rotary members, a cam track on each frame part, and jet-delivering means adapted to be turned by said rotary member and guided by said cam track so that the jets substantially follow the 100 contour of the work.

26. Apparatus for rail-cutting or the like, comprising two frame parts hinged above the rail and adapted to receive the same between them, rotary driving mechanism and guiding means mounted on each 105 110 115 120 125 130
